UNITED STATES PATENT OFFICE.

ANTON LUGER, OF VIENNA, AUSTRIA-HUNGARY.

SEALING DEVICE FOR JARS, &c.

SPECIFICATION forming part of Letters Patent No. 280,938, dated July 10, 1883.

Application filed February 19, 1883. (No model.)

To all whom it may concern:

Be it known that I, ANTON LUGER, of the city of Vienna, in the Empire of Austria-Hungary, have invented certain new and useful 5 Improvements in Sealing Devices for Jars and other Vessels, of which the following is a specification.

The object of my invention is to construct a sealing device which may be applied to vessels of any kind—such as cans, jars, bottles, &c.—and which may either be permanently or removably attached to the vessel to be sealed; and the invention consists of a ring-shaped band, having projections at one side for a 15 hinged strap applied to the cover, lid, or stopper, and guide-lugs and a projecting tooth or teeth at the opposite side for a toothed locking-bar, which is hinged to the strap and retained on the projecting tooth by a suitable 20 clamping device.

In the accompanying drawings, Figure 1 represents a vertical section of my sealing mechanism applied to the mouth of a jar or other vessel; Fig. 2, a plan view of the same 25 with the cover or lid removed. Fig. 3 shows in the same manner as Fig. 1 a modification of the sealing device. Fig. 4 shows the application of my sealing device to the half-cover of a metal can. Figs. 5, 6, and 7 are details of 30 the mechanism shown in Figs. 1 and 2, and Figs. 8, 9, and 10 are details of the arrangement shown in Fig. 3.

Similar letters of reference indicate corresponding parts.

35 In the Letters Patent granted to me heretofore for improvements in jars, which were numbered 266,375, and dated October 24, 1882, a sealing device is shown which is permanently connected with the jar or vessel. The sealing 40 device forming the subject of this application is independent of and separate from the vessel, and may be adjusted upon and taken off the same at will. It is evident that this locking or sealing device may be made of any size 45 or form, so as to be employed not only for cans, jars, and bottles, but also for any other and larger vessels.

This new locking or sealing device consists 50 of a ring-shaped metallic band, *a*, whose side diameter approximately corresponds to the outside of the neck or part near the

mouth of the vessel upon which it is to be used. The band *a* may be formed of two halves or of one piece or band open on one side. At this open part of the band *a* the 55 ends of the same are bent outward and edge-wise upward, in the manner shown in Figs. 1 and 2, so that an open space is left between the two ends. A screw or rivet, *c*, passes at about the middle of the band *a* through the 60 lower part of the ends *b*, by means of which screw *c* the band *a* is secured tightly around the neck of the vessel. To prevent a bending out of shape of ends *b* by the screw *c* being drawn too tight, a ferrule or small piece of 65 tube, *d*, may be placed upon screw *c*, as shown in Fig. 2. In place of tube *d*, a removable handle, as indicated in Fig. 1, may be placed upon said screw, which handle serves the same purpose. The lower end of the handle is attached in any suitable manner to the base of 70 the vessel. The upright ends *b* of band *a* are near their upper end provided with horizontal or nearly horizontal slots *b' b'*, of which, although but one is required, preferably two, or 75 even more, slots are arranged to compensate for any bending or giving of any of the parts. Into one of the slots *b'* the pin *e* of strap *f* is inserted, the slot permitting a lateral motion of pin *e*, so that the cover of the vessel and its 80 fittings can never be strained, and the former finds readily its seat on the jar or other vessel. The strap *f* is fitted between the ends *b* of band *a*, which ends or lugs may be of one piece with 85 band *a*, as described, or separate and fastened in suitable manner to the latter, as shown in Fig. 3. Strap *f* may be short and fastened to one side of the cover, lid, or stopper, or it may extend across to the opposite side of the mouth 90 of the vessel, where it carries a pin, *g'*, upon which swings the locking-bar *g*. This locking-bar is, on its inner side, serrated or provided with one or more teeth, *h*. These teeth *h* interlock with one or more teeth, *i*, arranged at the opposite side of band *a*. The tooth or 95 teeth *i* are situated between two projections or lugs, *k*, which carry a clamping device for preventing the accidental disengaging of the teeth *h* and *i*. This clamping device consists of a small plate, *l*, Fig. 6, having a stem, *m*, 100 which latter slides in a hole in the small plate *n*, that connects the lugs *k* at or near their end.

Plate *l* is guided by means of its two projections *o* in slots of lugs *k*, as shown in Fig. 4. Between the fixed plate *n* and the sliding plate *l* is interposed a spring, *g*, which serves to 5 press plate *l* upon the locking-bar *g*, and the latter against the band *a*, whereby the teeth *h* and *i* are held securely in engagement.

In Fig. 3 the locking-bar *g* is made in the shape of a link, as also shown in Fig. 9, in 10 which case the band *a* has only one projection *k*, which is provided with several teeth, *i*, to one of which the locking-link *g* is applied. The reason for having several teeth instead of one, either on the locking-bar *g* or on the band *a*, 15 is the same as that stated for providing the ends *b* with several slots, as already mentioned—viz., to compensate for the bending of any of the parts, or for the giving of the elastic packing-ring or gasket, where such is employed. 20

It is evident that the mechanism described can be fitted to any cover, lid, or stopper of any form, size, or material. As already mentioned, strap *f* may extend right across the 25 cover or stopper, and be of one piece; or two short pieces of metal, for carrying pins *e* and *g*, respectively, may be substituted therefor and fastened in suitable manner on opposite points of the cover, lid, or stopper.

As shown by Fig. 4, my sealing or locking 30 device may also readily be adapted for cans with a cover having a fixed portion, *t*, and a hinged portion, *u*. Where an elastic gasket is to be employed, I prefer to make the cover, lid, or stopper of two halves, between which 35 the gasket *r* is placed, as shown in Fig. 3, the parts being held together by a screw or rivet, *s*.

Having thus described my invention, I claim as new and desire to secure by Letters Patent—

The combination, with a cover, lid, or stopper 40 for vessels, of ring-shaped band *a*, having slotted lugs *b* at one side and a toothed projection, *i*, at the opposite side, with a strap, *f*, attached to the cover, lid, or stopper and hinged to the slotted lugs *b*, toothed locking-bar *g*, hinged to strap *f*, and a clamping device 45 embracing a fixed plate, a sliding plate, and a spring, by which the locking-bar *g* is held in engagement with the toothed projection *i*, substantially as and for the purpose described. 50

In testimony that I claim the foregoing as my invention I have signed my name, in presence of two witnesses, this 11th day of January, 1883.

ANTON LUGER.
